(57) CLAIM

The ornamental design for a compressible guitar pick, as shown and described.

DESCRIPTION

FIG. 1 is a top perspective view of a compressible guitar pick showing my new design;

FIG. 2 is a side perspective view of the compressible guitar pick shown in FIG. 1; and,

FIG. 3 is a front elevational view of the compressible guitar pick shown in FIG. 1.

The broken line showing of a fragmentary hand in FIG. 2 is for illustrative purposes only and forms no part of the claimed design.
